UNITED STATES PATENT OFFICE

134,702

DESIGN FOR A COMBINED FLOWER POT AND STAND

Charles William Stillwell, Huntington Park, Calif.

Application December 26, 1941, Serial No. 104,863

Term of patent 14 years

To all whom it may concern:

Be it known that I, Charles William Stillwell, a citizen of the United States, residing at 6420 Santa Fe Avenue, Huntington Park, in the county of Los Angeles and State of California, have invented a new, original, and ornamental Design for a Combined Flower Pot and Stand, of which the following is a specification, reference being had to the accompanying drawings, forming a part thereof.

Fig. 2 is a perspective view of the stand taken from a different angle, the flower pot shown in Fig. 1 being omitted.

I claim:

The ornamental design for a combined flower pot and stand, as shown.

CHARLES WILLIAM STILLWELL.
